UNITED STATES PATENT OFFICE

90,995

DESIGN FOR A CURTAIN OR THE LIKE

Max Sadinoff, Brooklyn, N. Y.

Application September 30, 1933. Serial No. 49,379

Term of patent 3½ years

To all whom it may concern:

Be it known that I, MAX SADINOFF, a citizen of the United States, residing at 1766 Union Street, in the borough of Brooklyn, city of New York, county of Kings, and State of New York, have invented a new, original, and ornamental Design for a Curtain or the like, of which the following is a specification, reference being had to the accompanying drawing, forming a part thereof.

The figure is a plan view of a curtain showing my new design.

The cross hatching appearing on the drawing represents the background of the fabric.

The broken away portion indicated by the dotted lines contains one row of figures identical with those illustrated adjacent thereto.

I claim:

The ornamental design for a curtain or the like, as shown and described.

In testimony whereof I have signed this specification.

MAX SADINOFF.
